US00D894791S

(12) **United States Design Patent** (10) Patent No.: **US D894,791 S**
Lin et al. (45) Date of Patent: ** Sep. 1, 2020

(54) **GOKART**

(71) Applicant: **NINEBOT (BEIJING) TECH. CO., LTD**, Beijing (CN)

(72) Inventors: **Ji Lin**, Beijing (CN); **Yongjie Li**, Beijing (CN)

(73) Assignee: **NINEBOT (BEIJING) TECH. CO., LTD**, Beijing (CN)

(**) Term: **15 Years**

(21) Appl. No.: **35/507,446**

(22) Filed: **Feb. 28, 2019**

(80) **Hague Agreement Data**

Int. Filing Date: **Feb. 28, 2019**

Int. Reg. No.: **DM/202839**

Int. Reg. Date: **Feb. 28, 2019**

Int. Reg. Pub. Date: **Sep. 20, 2019**

(30) **Foreign Application Priority Data**

Aug. 31, 2018 (CN) 2018 3 0490460
